UNITED STATES PATENT OFFICE.

MICHAEL G. CLARK, OF DALLAS, TEXAS.

HARNESS-SADDLE.

SPECIFICATION forming part of Letters Patent No. 614,838, dated November 29, 1898.

Application filed March 15, 1898. Serial No. 673,931. (No model.)

To all whom it may concern:

Be it known that I, MICHAEL G. CLARK, a citizen of the United States, residing at Dallas, in the county of Dallas and State of Texas, have invented new and useful Improvements 5 in Harness-Saddles, of which the following is a specification.

My invention relates to improvements in harness-saddles; and it consists of certain 10 features of construction and combination of parts by which a lighter harness-tree may be used and the pads are capable of adjustment either up or down or may be turned clear 15 around, as will be hereinafter more fully described and claimed.

In the accompanying drawings similar letters of reference refer to similar parts.

Figure 1 is a perspective view of a harness-saddle provided with my invention. Fig. 2 20 is a front view of a portion of a harness-saddle, showing the pads adjusted in their highest position. Fig. 3 is an end view of a portion of the harness-saddle, showing the pads in their lowered position. Fig. 4 is a sectional view through the pad and harness-saddle at the terret. Fig. 5 is a detailed perspective view of the various parts. Fig. 6 is 25 a front view of a portion of a harness-saddle, showing the pads turned around, so that the thinner portion shall be at the top and the thick portion at the bottom. Fig. 7 is a perspective end view of the pad-plate. Fig. 8 is 30 perspective end view of a portion of the sliding washer. Fig. 9 is a perspective view of the terret-nuts. Fig. 10 is a perspective view 35 of the terret-nuts cast together and with a connecting-bar.

A represents a harness-saddle which may be made without the ordinary heavy metallic 40 tree heretofore used and may consist of a light metallic tree and the heavy single strap-leather skirts B and the jockey C, stitched to the skirt B. Through the skirt B and jockey C and upon both sides thereof are perforations to receive the retaining-bolts D and D' 45 and the terrets E and E'.

The pads F and F' are formed upon a pad-plate G, which may consist of cast or sheet metal formed either of a single piece or two or 50 more riveted or otherwise fastened together. I have shown it and prefer to make it of light sheet metal parallelogram in form, the sides

thereof folded back upon the bottom and up and in, forming the outer flanges g' and the inner flanges g² g³. Heavy pieces of leather 55 are then passed along the outer flanges g', to which the cover f of the pads is securely tacked. Between the bottom of the pad-plate G and the inner flanges g² and g³ there is slipped the sliding leather washer H, to the 60 under side of which there have been tacked the terret-nuts I and I', the screw-threaded upper portion of which passes entirely through the leather.

The terret-nuts I and I' may be made with 65 their wings heavier and cast so as to have a connecting-bar, as shown in Fig. 10. When so constructed, they can be used without the intervention of the sliding leather washer H and take the place thereof.

To construct the saddle, the sliding washer H, carrying the terret-nuts I and I', is slipped into the pad-plate G. The heavy leather J, to which the outer covering of the pad is tacked, is then slipped over the tree and the 70 leather covering f brought up and around the pad and the edges thereof tacked to the leather. The space between the leather covering and the under side of the pad-plate is then filled with hair or other substance to 75 form a cushion or pad. The terrets and locking-bolts are then passed through the jockey, skirt, and housing and engage the terret-nuts I and I' in the sliding washer H of the pads. This form of construction, which enables the 80 use of a lighter metallic tree than heretofore used, produces a saddle having a smooth throat, the saddle-hook and its retaining-bolt being mounted upon the metallic tree carrying the skirts. The housing covers the under 85 side of the saddle-hook A' and presents, therefore, a perfectly smooth throat.

The saddle-hook A' takes the place of the rein-hook ordinarily employed in connection 90 with harness-saddles.

By means of this invention the heavy metal saddletrees heretofore used may be entirely 95 done away with, a lighter flat pad-plate used in place thereof, and the pads are capable of an upward and downward adjustment to enable them to be adapted to the form of the back of the horse, and thus do away with all abrasion and chafing of the horse's back.

Various modifications of the shape and con-

figuration of the pad-plate may be made without departing from the spirit of my invention, which consists, primarily, in providing an independent plate upon which the pad is formed and which carries a sliding washer, which may be of either leather, metal, or wood, to which are attached terret-nuts.

Having thus fully described my invention, what I desire to claim and secure by Letters

10 Patent is—

15 1. The combination in a pad for harness-saddles, of a plate provided with inwardly and outwardly projecting flanges, a sliding washer engaging therewith, and carrying terret-nuts, substantially as described and for the purpose set forth.

2. The combination in a harness-saddle of a skirt and jockey, provided with perforations to receive terrets and locking-bolts; pads formed upon pad-plates provided with inwardly and outwardly projecting flanges; a sliding washer carrying terret-nuts adapted to engage with the terrets and locking-nuts, substantially as described and for the purpose set forth.

20 25 In testimony whereof I have hereunto set my hand in the presence of two subscribing witnesses.

MICHAEL G. CLARK.
